JOHN WILKINSON, OF SYRACUSE, NEW YORK, ASSIGNOR TO H. H. FRANKLIN MANUFACTURING COMPANY, OF SYRACUSE, NEW YORK, A CORPORATION OF NEW YORK.

AIR-COOLING SYSTEM FOR INTERNAL-COMBUSTION ENGINES.

1,170,716.

Specification of Letters Patent.

Patented Feb. 8, 1916.

Application filed December 27, 1910. Serial No. 599,245.

To all whom it may concern:

Be it known that I, JOHN WILKINSON, of Syracuse, in the county of Onondaga and State of New York, have invented a new and useful Air-Cooling System for Internal-Combustion Engines, of which the following is a specification.

My invention has for its object a particularly simple and efficient air cooling system for internal combustion engines of motor vehicles; and it consists in the combinations and constructions hereinafter set forth and claimed.

In describing this invention reference is had to the accompanying drawing in which like characters designate corresponding parts in all the views.

Figure 1 is a longitudinal sectional view, partly in elevation of a portion of a vehicle embodying my invention, parts of the engine being omitted. Fig. 2 is a plan of parts seen in Fig. 1, the hood being removed. Fig. 3 is a sectional view on line "A—A" Fig. 2, the engine and other parts being omitted. Fig. 4 is a detail view of one of the cylinders and flanges set therein.

The invention comprises, generally, a casing, for an engine having a plurality of air cooled cylinders, a transversely disposed partition dividing the casing into two compartments, the upper of said compartments having an inlet opening, and the lower of the compartments an exit opening, said partition having means individual to the cylinders of the engine for affording communication between the two compartments and for bringing the air in its passage from one compartment to the other into intimate contact with the cylinders throughout a major part of the length thereof, and a peripherally discharging suction fan, located adjacent the said exit opening, and of the type which will move a large volume, or body, of air comparatively slowly.

In the illustrated exemplification of my invention, 1 indicates the side sills of the frame, or chassis, of a motor vehicle, 2 the dash-board thereof and 3 the engine, consisting of a base frame housing the crank-shaft, and a plurality of upright cylinders arranged in tandem formation and equipped with suitable heat conducting ribs, or fins, which are preferably formed separate from the cylinders and set into grooves therein,

as shown in Fig. 3, and which preferably extend lengthwise of the cylinders.

The casing preferably houses the entire engine and comprises a lower section, or boot 6, an upper section, or hood 21, and a transversely extending partition dividing the casing into upper and lower compartments. The lower section, or boot 6, is secured at its side upper edges to the sills 1, and includes a front plate, or wall 8, a substantially semi-cylindrical body portion flaring downwardly and rearwardly from the front plate, and a rear wall 15 having an opening 16 therein. The upper section, or hood, of the casing, comprises a substantially semi-cylindrical plate, abutting at its rear edge 70 against the front face of the dash-board 2 and having side flanges 23 adapted to rest upon the sills 1, a front plate having an opening 22 therein, and brackets 24, carried by the front plate and engaging pins 25 extending inwardly from the sills 1, for providing a pivotal support about which the hood may be swung in order to obtain access to the cylinders.

The partition includes a substantially horizontally disposed top plate 7 extending lengthwise of the casing in a plane intersecting the cylinders between the ends thereof, and provided at its rear end with an upwardly extending flange 19 secured to the front face of the dash-board 2, and a downwardly extending wall 14 having therein an opening 16 cooperating with the opening 16 for providing the air exit from the casing. The partition further includes a front plate 12 having a portion of its upper edge secured to the plate 7, and its lower edge secured to the upper edge of the front wall 8 of the boot, and side plates 9, secured at their upper side edges to the side edges of the plate 7 and provided at their lower side edges with flanges 11 which rest upon the sills 1, and at their front edges with flanges 13 overlapping portions of the upper edge of the plate 12.

The major portion of each plate 9 is preferably displaceable so as to afford access to the lower compartment of the casing and for this purpose the upper edge of each of said major portions is preferably hinged to the edge of the plate 7 in any suitable manner. The plate 7 is provided with openings therein individual to the cylinders and the pas-

sage-ways afforded thereby are prolonged, or extended, above and below the plate 7, by means of cylindrical shells 20. Each shell 20 is of slightly greater diameter than the cylinder associated therewith and terminates at its upper end at a point adjacent the upper end of such cylinder and at its lower end a short distance above the lower ends of the heat conducting ribs with which the cylinder is equipped.

The peripherally discharging fan is designated 26, and is mounted on the crank-shaft 17. This fan preferably extends on opposite sides of the plane of the rear face of the dash board 2 and is formed with a discoidal head 27 closing its rear side, an annular head 28 at its front side and blades 29 between said heads. The annular head is formed with a large intake opening approximating in diameter the diameter of the exit opening of the casing, and arranged in close juxtaposition to and concentric, and in open communication therewith. The fan is also provided with an axial chamber opening inwardly from its rear side and into which a driven member 31 extends, the driven member 31 being connected to the fan in order to receive motion therefrom by means of clutch members, as disks, or flat rings 32, and 33, associated respectively with the fan and the driven member. The lower portion of the fan is inclosed by a deflector 30 extending rearwardly from the boot or pan 6.

In the operation of the described mechanism air enters the opening 22 and passes rearwardly in the upper compartment of the casing, and through the action of the fan 26 it is drawn down into the lower compartment through the shells 20, so that each cylinder is brought into intimate contact throughout a major portion of its length with a substantially uniform, or equal, amount of air, and as the fan is of the type which moves a comparatively large body, or volume, of air comparatively slowly, the cylinders are cooled in a highly efficient manner.

What I claim is:—

1. The combination with an engine having a plurality of upright cylinders arranged tandem, and provided with heat radiating ribs, an inclosing casing comprising a shoe surrounding the lower portion of the engine, and having a closed front end, and an exit opening in its rear end, a hood having a closed rear end and an opening in its front end, and a partition dividing the casing into upper and lower compartments and having vertical passage-ways therein individual to the cylinders through which the cylinders extend, and an exhaust fan arranged adjacent the opening in said shoe.

2. The combination with an engine having a plurality of air cooled cylinders arranged tandem, of an inclosing casing for the en-

gine having inlet and exhaust openings therein, a transversely arranged partition wall dividing the casing into upper and lower compartments, said inlet opening communicating directly with one of the compartments, and the exhaust opening with the other compartment, a shell individual to each cylinder supported by the partition and extending on opposite sides thereof and providing a passage way between the said compartments, each shell being arranged concentric with the cylinder with which it is associated, and an exhaust fan arranged adjacent the exit opening in the casing.

3. The combination with an engine provided with a plurality of cylinders each equipped with peripheral ribs, or fins, of a casing, a transversely disposed partition dividing the casing into upper and lower compartments, said casing having an inlet opening communicating directly with the upper compartment, and an exhaust opening communicating directly with the lower compartment, a shell associated with each cylinder, said shells being supported by the partition and opening at their upper ends into the upper compartment of the casing and at the lower ends within the lower compartment thereof, and an exhaust fan arranged in close juxtaposition to said exit opening.

4. The combination with an engine provided with a plurality of cylinders each equipped with peripheral ribs, or fins, of a casing, a transversely disposed partition dividing the casing into upper and lower compartments, said casing having an inlet opening communicating directly with the upper compartment and an exhaust opening communicating directly with the lower compartment, a shell associated with each cylinder, said shells being supported by the partition and opening at their upper ends into the upper compartment of the casing and at the lower ends within the lower compartment thereof, and an exhaust fan having an axial intake and a peripheral discharge, said fan being located with its intake arranged concentric with said exit opening and in close juxtaposition thereto.

5. The combination with the side sills of an automobile chassis, and an engine having its base supported by the said sills and having a plurality of upright cylinders arranged tandem and equipped with heat conducting ribs, of a casing inclosing the cylinders comprising, a boot having a front wall, a rearwardly flaring body portion with its side edges attached to the sills, and a rear wall provided with an opening, a partition having side portions resting on the sills, a front wall attached to the front wall of the boot, and a depending rear wall provided with an opening co-operating with the opening in the rear wall of the boot for providing an exit opening for the casing, and a

- hood pivotally supported at its front end from the sills, and having its side edge supported by the sills, said hood having an inlet opening therein, a shell disposed concentrically of each cylinder, said shells being carried by and extending through said partition, and having their opposite ends open, and an exhaust fan arranged in close juxtaposition to said exit opening.
10. 6. In a motor vehicle, the combination with a frame, an internal combustion engine comprising a plurality of cylinders arranged one behind the other, and a crank shaft; of a casing inclosing the engine and including an upper wall extending transversely of the cylinders and having openings individual to the cylinders and door sections on opposite sides of the transversely extending wall and having their margins resting on the contiguous parts of the frame, a hood arranged above the transversely extending wall and resting on the frame and on the margins of the door sections, the casing also having an exit opening below the transverse wall, and a peripherally discharging suction fan actuated by the crank shaft and arranged to exhaust air through the said exit opening, substantially as and for the purpose specified.
15. 7. In a motor vehicle, the combination with a frame including sills, and an internal combustion engine arranged between the sills and comprising a plurality of cylinders arranged one behind the other, and a crank shaft; of a casing inclosing the engine and including an upper wall extending transversely of the cylinders and having openings individual to the cylinders and door sections hinged to opposite sides of the transverse wall and having their margins adapted to
- rest on the sills, the casing also having an exit opening below the transverse wall, and a hood arranged above the transverse wall and resting at its sides on the sills and on the margins of the door sections, substantially as and for the purpose set forth.
8. The combination with the side sills of an automobile chassis and an engine having its base supported by the sills and having a plurality of upright cylinders arranged tandem and equipped with heat conducting ribs, of a casing inclosing the cylinder comprising a boot having an intact front wall and a rearwardly extending body portion having its side edges attached to the sills, a partition having its side portion resting on the sills, and a front wall coöperating with the front wall of the boot, said partition and boot having coöperating openings at corresponding ends forming an exhaust opening, a vertical shell individual to each cylinder disposed concentrically thereof and extending through the partition, an exhaust fan arranged in juxtaposition to said exit opening, and a hood pivotally supported at its front end from the sills and having its side edges supported by the sills, said hood having an inlet opening therein, substantially as and for the purpose described.
- In testimony whereof, I have hereunto signed my name in the presence of two attesting witnesses, at Syracuse, in the county of Onondaga, in the State of New York, this 21st day of November, 1910.

JOHN WILKINSON.
